CLAIM

I claim the ornamental design for a child swaddle apparatus, as shown and described.

DESCRIPTION

FIG. 1 is a side perspective view of a child swaddle apparatus; FIG. 2 is a front view of FIG. 1; FIG. 3 is a rear view of FIG. 1; FIG. 4 is a side view of FIG. 1; and, FIG. 5 is a bottom perspective view of FIG. 1. The buckle and straps that are shown in broken lines in FIG. 3 are for illustrative purposes only and do not form part of the claimed design.
